UNITED STATES PATENT OFFICE

2,474,427

HAIR DRIER

Ernest Kaiser Kending, Flushing, N. Y.

Application October 23, 1945; Serial No. 623,985

4 Claims. (Cl. 34—99)

1

The present invention relates to improvements in hair driers, more particularly to a new type of hair drier which is efficient, requires little space, is easy to manufacture, light in weight, convenient for packing and shipping, fireproof, safe, economical, which can be used in connection with any source of air under pressure, and which is particularly adapted to be used at home, as a home appliance.

The object of the invention is the provision of a practical hair drier particularly for drying women's finger-waved hair and of chemically set waves which drier can be operated by the general public without training and in full safety re: fire and accident.

Aside from the above features, an important object of the new hair drier is that, although it uses air under relatively high pressure, no hot air is blown downward on the face of the user.

Another object of the invention is the provision of a hair drier which uses air under pressure and blows it onto the scalp and hair exclusively and in such a way that water or liquid with which the hair has been treated is effectively removed and shaken out and evaporated even from the minute scales on the surface of the hairs.

An object of the invention is the provision of a hair drier in which no metallic surfaces are adjacent the hair whereby undesired heating by radiation is avoided. The new hair drier operates substantially on heat transfer by convection.

An object of the invention is the provision of a hair drier which can easily be adjusted to suit any configuration and position of the scalp.

An object of the invention is the provision of a hair drier using electrically heated air from any source of air under pressure whereby the heating current is automatically shut off whenever the device reaches an undesired high temperature and whenever the person whose hair is being dried desires shutting off of the heating current and whenever that person departs from the device.

An object of the invention is the provision of a hair drier using electrically heated air from any source of air under pressure whereby burning out of heating elements due to contact with too much air-oxygen is made impossible.

An object of the present invention is to provide a hair drier in which all the above enumerated desirable features are obtained by extremely simple means which are available and need either no or slight modifications only.

Further and other objects of the present in-

vention will be hereinafter set forth in the accompanying specification and claims and shown in the drawings which, by way of illustration, show what I now consider to be a preferred embodiment of my invention.

In the drawings:

Fig. 1 is a part sectional side view of the apparatus according to the invention.

Fig. 2 is a rear view of the device shown in Fig. 1.

Fig. 3 is an electric wiring diagram of the apparatus according to the invention.

Like parts are designated by like numerals in all figures of the drawings.

Referring more particularly to the drawings, numeral 1 designates an electric strip element which is enclosed so as not to expose it to the oxygen of the air to avoid brittleness and burning of the resistance wire. The strip is located 20 in a vertical tube 2 of sufficient cross section and length to give the air rushing through it a chance to pick up the heat efficiently. Both terminals 3 of the electric element are in its upper end.

The electric heater 1, 2 is within a decorative 25 enclosure 4 extending from the base 5. Through this enclosure extends also the lower portion of the standard column 6 supported by pedestal 5.

Tube 2 is fastened to rod 6 by suitable brackets.

A panel 7 is connected to the upper portion of 30 rod 6 within enclosure 4. Four electric terminals are mounted on panel 7. Terminals 8 and 9 receive the ends of the electric wires 10 leading to a wall plug 11. One end of the heating wire 12 in element 1 is connected with terminal 9.

The other end of wire 12 is connected with a thermal switch 13 which is in physical contact with the outer wall of the heater housing 2. It is actuated by the temperature of the upper part 35 of the heater and cuts off the current if said

temperature is between 260° and 300° F. according to the rules of Fire Underwriters. I propose to use what is known in the trade as a Klixon switch. Any other suitable device such as one which carries current overload but melts at 300°

45 F. and then interrupts the current and which can be replaced, may be employed. From the thermal switch 13 the current passes a standard current overload fuse 14 fastened to the insulated panel 7 and from this fuse to terminal 15 of the 50 distributing box.

A momentary switch 16 for example as is known in the trade as Micro switch is connected through several feet of wire to points 15 and 17 of the distributing box. Switch 16 is open all the time unless deliberately closed by the person

whose hair is being dried. The switch requires only a very gentle pressure and does not tire the person during the half hour or so of drying operation. The combination of this switch with the hair drier is a novel safety measure and of paramount importance in such home appliance. Should, for instance, the person in the chair leave, being called away by phone, door bell, etc. the current must at once be interrupted, particularly if by some unforeseen circumstance the supply of fresh air to the heater should be interrupted.

The air to be used enters the bottom of heater 1, 2 through a flexible tube 18. This tube may be connected to the pressure side of a vacuum cleaner, after disconnecting of the dust bag, or to any suitable source of pressure air such as, for example, an air conditioning system or room outlets of an air distributing system having a common pressure air producer in another part of the building. The hot air leaves the heater through a V-shaped member 19 connected to the top of the heater.

It is to be noted that the lower part of the drier, i. e. the parts described so far, is a compact portable unit by itself which is small enough to be shipped in a small carton or suitcase. It can be used for instance as a room heater, by opening lid 20 on outlet 19.

The upper part of the device according to the invention comprises the relatively flat drying cap 21 with its flexible tubing 22 which brings the warm pressure air from the outlet 19 of the heater to the cap, the vertical rod or column 23 which is removably, yet rigidly connected to rod 6 and forms therewith the standard around which the drying equipment is built, the sleeve member or clutch 24, and the cap supporting rod 25 rigidly connected to clutch 24. The whole upper part can be shipped easily in a small carton or case.

The flexible tubing 22 is bent away from the chair, so as not to molest the person in the chair. The upper end of the tubing is fastened into the air inlet of the drying cap 21. The weight of the tubing, as far as not supported by the heater housing outlet, is carried by the clutch 24 at the upper end. The tube extends slideably through the sleeve portion 26 of the clutch. The upper end of the flexible tube can be moved up or down by sliding the slide member or clutch 24 on rod 23.

The cap comprises a bottom ring 27 made of non-metallic and preferably somewhat flexible tubing to which the flexible hose 22 is connected for air supply. The size of ring 27 is such as to loosely fit the average size head at the line above the ears and beginning of the scalp on the forehead. A larger size may be made for large heads and a small size for small heads as it is an object of the invention to provide a cap which does not leave an appreciable clearance between the scalp and the inside of the cap for reasons to be explained later. A rounded piece of tubing which may be made of the same material as ring 27 is connected to said ring for air flow and forms the crown 28. The inside height of the crown is preferably not greater than one half of the length of the largest lateral dimension of the opening at the bottom of the cap. The cap is shaped somewhat like a turtle back or a cobra head in contradistinction to the dome shaped hoods of conventional hair driers. The cap according to the invention reaches not farther down than just to touch the top of the ears, allowing a fairly close fit to the head. The

bottom ring 27 is provided with small air outlet holes 29 adapted to let the air escape in jets of high air velocity and directed upward and toward the scalp. The apertures 29 are in the upper inner quarter of the tube cross section at an angle of 25° to 50° above the center line of the bottom ring. Both lower quarters of the cross section of the tube that forms the crown are provided with holes 30 ejecting air at an angle of 25° to 50° from the horizontal line on both sides of the tube. The total area of the small air holes in the skeleton of the cap formed by tubes 27 and 28 should approximate the cross section of the air inlet into the heater housing to maintain the desired air pressure and speed of the air jets. The skeleton of the cap described supra is covered by a material that permits the warm air inside the cap to do its work, yet is porous enough to permit a direct escape of the air that has become humid.

With the air cap as described the air jets impinge on the scalp and the air is blown at considerable velocity between and underneath the hair and acts mechanically on the hair shaking the minute droplets therefrom and effectively promoting evaporation and removal of the moisture. The parts of the cap from which the jets originate are so close to the scalp that the air has not yet expanded and not yet expended its kinetic energy when it reaches the hair. The moisture laden air is removed quickly, equally and substantially upward from all parts of the scalp and no hot air flows down the face causing discomfort.

35 The forward part of the cap is suspended from rod 25 by a flexible means 33 extending around the crown forming tube 28 and ending in a hook 34. By sliding the hook along the light rod 25 and by moving the slide member 24 up and down, the cap can be adjusted to a suitable angle and elevation for the head of the person whose hair is being dried. Only a light touch of the fingers of one hand is required to move the cap into the the most efficient and comfortable position.

40 45 While I believe the above described embodiment of my invention to be a preferred embodiment, I wish it to be understood that I do not desire to be limited to the exact details of design and construction shown and described, for obvious modifications will occur to a person skilled in the art.

I claim:

1. A portable pressure warm air hair drier, including, in combination, a standard, a longitudinal electric air heater disposed substantially parallel to the lower portion of said standard and connected to it for support, a cold pressure air intake means at the lower portion of said heater and a warm air outlet means connected with the upper portion of said heater, a slide means vertically movably connected with the upper portion of said standard, an air conduit connected with said outlet means and extending through said slide means, a support member connected with said slide means, and a drier cap depending from said support member and comprising a warm air discharge means connected with said air conduit.

2. A portable pressure warm air hair drier, including, in combination, a base, a standard extending therefrom, an upright air heater resting on said base and connected to said standard, a cold pressure air intake means at the lower portion of said heater and a warm air outlet means connected with the upper portion of said heater, 70 a slide member vertically movably connected with

the upper portion of said standard, an air conduit connected with said outlet means and extending through said slide member, a support member connected with said slide member, and a drier cap depending from said support member and comprising warm air discharge means connected with said air conduit.

3. A portable pressure warm air hair drier, including, in combination, a standard, an electric air heater comprising a longitudinal upright conduit and a longitudinal electric heating element disposed therein, said heater being disposed substantially parallel to the lower portion of said standard and connected to it for support, a cold pressure air intake means connected with the lower portion of said conduit and a warm air outlet means connected with the upper portion of said conduit, a slide means vertically movably connected with the upper portion of said standard, an air conduit connected with said outlet means and extending through said slide means, a support member connected with said slide means, and a drier cap depending from said support member and comprising warm air discharge means connected with said air conduit.

4. A portable pressure warm air hair drying apparatus, including, in combination, an electric heater disposed in the lower portion of said apparatus and comprising a cold pressure air intake means and a warm pressure air outlet means, a column member, a slide member vertically dis-

placeable thereon, a support means extending from said slide member, a drier cap depending from said support means and comprising warm air discharge means, and flexible air conduit means connected with said outlet means, extending through said slide means, and being connected with said air discharge means.
